United States Patent Office

Des. 183,860
Patented Nov. 4, 1958

183,860.

COMBINED FOOT REST AND STORAGE COM- PARTMENT FOR A DRAFTING TABLE

Paul L. Paulsen and Claude G. Kanzelberger, Two Rivers,
Wis., assignors to Hamilton Manufacturing Company,
Two Rivers, Wis., a corporation of Wisconsin

Application October 7, 1957, Serial No. 47,991

Term of patent 14 years

(Cl. D33—14)

Fig. 2

Figure 1 is a perspective view of a combined foot rest and storage compartment for a drafting table showing our new design; and

Figure 2 is a sectional view taken on the line 2—2 of Fig. 1.

The back and side not shown are plain and unornamented.

The dotted line indication of a drafting table in Figure 1 is for illustration purposes only.

We claim:

The ornamental design for a combined foot rest and storage compartment for a drafting table, substantially as shown and described.

References Cited in the file of this patent

Machine Design, May 1935, page 68, Drawing desk.
Hasluck Woodworking catalog, 1907, rec'd. U. S. Patent
Office, March 9, 1948, page 231, Figure 742, Coal trough.